UNITED STATES PATENT OFFICE

CHARLES ADLER, JR., OF BALTIMORE, MARYLAND, ASSIGNOR TO THE ADLER SAFETY CONTROL COMPANY, OF BALTIMORE, MARYLAND, A CORPORATION OF MARYLAND

DESIGN FOR A TRAFFIC SIGNAL CASING

Application filed May 19, 1931. Serial No. 39,897. Term of patent 14 years.

To all whom it may concern:

Be it known that I, CHARLES ALDER, Jr., a citizen of the United States, residing in the city of Baltimore and State of Maryland, have invented a new, original, and ornamental Design for a Traffic Signal Casing, of which the following is a specification, reference being had to the accompanying drawings, forming a part thereof, showing my design, in which:

Figure 1 is a front elevation of a traffic signal casing, showing my new design; and Figure 2 is a side elevation thereof.

I claim:

The ornamental design for a traffic signal casing, as shown.

In testimony whereof I affix my signature.

CHARLES ADLER, JR.
